UNITED STATES PATENT OFFICE

164,772

AIR CONDITIONING AND CIRCULATING
UNIT

Charles W. Hahl, Pomona, Calif.

Application June 12, 1950, Serial No. 10,464

Term of patent 14 years

(Cl. D62—4)

To all whom it may concern:

Be it known that I, Charles W. Hahl, a citizen of the United States, residing at Pomona, in the county of Los Angeles and State of California, have invented a new, original, and ornamental Design for an Air Conditioning and Circulating Unit, of which the following is a specification, reference being had to the accompanying drawing, forming part thereof.

Figure 1 is a view in side elevation of an air conditioning and circulating unit showing my new design.

Figure 2 is a top plan view of the air conditioning and circulating unit of Figure 1.

The other side of the unit, not shown, is like that illustrated in Fig. 1.

I claim:

The ornamental design for an air conditioning and circulating unit, substantially as shown and described.

CHARLES W. HAHL.
